United States Patent Office

Des. 222,838
Patented Jan. 11, 1972

222,838

KITE

Robert M. Ferguson, Dallas, Tex., and Lindell O. Carpenter, Rye, N.Y., assignors to Container Corporation of America, Chicago, Ill.

Filed Sept. 10, 1970, Ser. No. 24,938

Term of patent 14 years

Int. Cl. D21—01

U.S. Cl. D34—15

FIG. 1 is a perspective view of the kite, as viewed from the bottom thereof, showing our new design;

FIG. 2 is a bottom plan view thereof;

FIG. 3 is a top plan view thereof;

FIG. 4 is a side elevational view thereof;

FIG. 5 is an end view thereof with kite in its normal flying position;

FIG. 6 is an end view thereof with the bottom side of the kite facing upward; and

FIG. 7 is a perspective view thereof as viewed from the top of the kite.

We claim:
The ornamental design for a kite, as shown.
